[57] ABSTRACT

Disclosed is a conventional apparatus for directing molten, mineral slag onto a spinner rotating on a horizontal axis with annularly arranged steam jets directed parallel to the rotational axis stripping the slag from the spinner and fiberizing it. This conventional fiber forming system is utilized with a collecting tube having a conical entry portion which is concentric with and faces the stream of fiberized material projected by the steam jets. The spacing of the mouth of the entry portion from the point of entry of the slag into the steam jets is such as to minimize entry of shot or unfiberized slag into the collecting tube. The fiberized material is further refined or stripped of unwanted particles by passing it through an inclined portion of the collecting tube and, sequentially, through two, cyclone-type centrifugal separators before collecting it in a conventional bagging apparatus.

MINERAL FIBER PRODUCTION METHOD AND APPARATUS

BACKGROUND OF THE INVENTION

Apparatus and a process for the production of mineral fiber are disclosed in a U.S. Pat. to Downey No. 2,646,593. In the process disclosed a gravity-type collecting chamber is utilized to collect the fiber subsequent to its formation. With the advent of the energy crisis application of mineral fibers as thermal insulation to domestic, commercial and industrial structures has become increasingly important and widespread. In applying thermal insulation to existing structures, the primary and most effective form of application is by blowing-in the fiber using specialized equipment. Such specialized equipment is sensitive to the presence of unfiberized particles or "shot" in the material moving through it. The maintenance cost is decreased and the service life appreciably lengthened for such equipment by a refining of the fiberized material so that the presence of shot is minimized or eliminated. The method and apparatus of the present invention provide improved separation of shot from the fiberized material prior to its final accumulating. The conventional, large collecting chamber is eliminated as are other moving components customarily utilized such as conveyor screen, rotary screen cleaning system and the granulator or hammermill often necessary to reduce the product to the desired consistency. The product resulting from the method and apparatus of the present invention is characterized by the absence of unfiberized material and is particularly adapted for application by blow-in apparatus.

BRIEF DESCRIPTION OF THE DRAWINGS

FIG. 1 is a schematic view of the interconnected apparatus utilized to practice the method of the present invention.

FIG. 2 is a side sectional view of a portion of the structure shown in FIG. 1 and illustrating the positional relation of the components shown.

FIG. 3 is a schematic side sectional view of the dry centrifugal, or cyclone, type of separator shown in FIG. 1.

FIG. 4 is a schematic, side elevational view of the rotary valve component shown in FIG. 1.

DESCRIPTION OF THE PREFERRED EMBODIMENT

Referring initially to FIG. 1, a conventional means for producing a stream of molten slag material is indicated generally at 10 and, as is shown particularly in FIG. 2, this apparatus may include a spout or chute 11 down which a stream of molten slag 12 progresses. The molten slag may be tapped from a cupola (not shown) as is conventional. The molten slag falls from the end of the chute onto the inner marginal area of a generally cup-shaped spinner 13 which is rotated by a shaft 14, the shaft being rotated by a power means indicated generally at 16 in FIG. 1. It will be understood that, as is conventional in forming mineral fiber, rotation of the spinner 13 will cause finally divided streams of molten slag to move tangentially outwardly from the periphery of the spinner.

The tangentially moving streams of slag are projected horizontally and fiberized by means of an annular array of steam jets 16, the high velocity steam issuing from

the jets, indicated at 16a in FIG. 2, intersects the outwardly moving streams of slag and projects them horizontally rightwardly as viewed in FIG. 2. The annular array of steam jets 16 are disposed in an annular steam header 17 which is supplied by the pipe 18.

The horizontally projected, fiberized material is received in a collecting tube indicated generally at 21 in FIG. 1 and composed of an inclined portion 21a, a horizontal portion 21b and an open receiving end 21c. The open receiving end 21c of the collecting tube 21 is spaced from the point of entry of the slag streams into the steam flow and the magnitude of this spacing is indicated at A in FIG. 2. The diameter of the open end 21c of the collecting tube is indicated at B in FIG. 2. 15 The diameter of the end 21c of the tube is somewhat smaller than the diameter of the tube at a point spaced rightwardly from the end 21c so that the horizontal portion 21b of the tube has a slight conical configuration. In a preferred form of the apparatus the dimension A 20 is approximately 24 inches and the diameter B is 22 inches, the remaining portion of the tube 21 being of a uniform 24 inches in diameter. Small variation from these dimensions are possible without losing the advantages of the system, however, the dimensions set out 25 appear to produce optimum results. The inclined portion of the tube 21 is preferably arranged at an angle of approximately 40° from the horizontal.

The upper portion of the tube 21 is provided with a horizontal portion 21d which communicates with the 30 interior of an initial cyclone-type centrifugal separator indicated generally at 31 and shown in detail in FIG. 3. As may be seen in FIG. 3, the entry portion 21d of the tube 21 is flattened in configuration somewhat so that air and entrained material moving through the tube are 35 fed in a radially thin sheet tangentially into the separator.

The separator 31 is of conventional construction and this type of separator is commonly referred to as a "cyclone." Referring particularly to FIG. 3, the separator 40 has a lower, cone shaped body 31a communicating with a lower discharge tube 31b. Extending from the upper end of the cyclone 31 is a tubular discharge duct 31c which extends a distance into the body of the cyclone. Various forms of air moving means may be utilized for drawing air through the cyclone and, as here 45 shown, takes the form of the vane axial fan 32 driven by the motor 33.

Referring to FIG. 3, as air with entrained fiberized material is drawn into the cyclone through the tube 21d 50 by the fan 32, two distinct vortices are established in the cyclone. One is a large-diameter vortex descending helically down the cone shaped body portion of the cyclone and identified at 34. The other, identified at 34a, is an ascending helix of smaller diameter which extends 55 upward from the region of the outlet tube 31b, through the inner cylinder provided by the inwardly extending end of the tube 31c and through tube 31c to atmosphere. The air and entrained material, moving in the outer vortex path 34, separates at the base of the cyclone and the air from the outer vertical stream joins the rising inner vortex flow of air. In its passage from the inlet 21d to the apex of the cone, the entrained, fiberized material remains close to the outer wall, because of centrifugal force, and passes out the outlet 60 tube 31b with a minimum of re-entrainment of the fiberized material into the upper vortex. The operation of the cyclone 31, as described above, is conventional 65

and the cyclone functions to concentrate the fiberized material and drop it through the lower discharge duct 31b.

Referring to FIGS. 1 and 4, a rotary unloading valve is disposed in the tube or discharge duct 31b, the valve being shown in schematic detail in FIG. 4 and identified generally at 41. The use of the valve is necessary because the discharge duct 31b operates at negative pressure and must be sealed so that air cannot enter through the tube 31b. If air in any quantity were permitted to enter tube 31b, the suction at the inlet tube 21d would be destroyed, and the admission of air through the discharge duct 31b would further seriously interfere with the vortical separation necessary for the operation of the cyclone. An independently rotated shaft 41a rotates a series of radial vanes 41b in counter-clockwise direction as viewed in FIG. 4, these vanes serving to accumulate the fiberized material, indicated at 51 and drop it through the discharge 41c of the rotary valve.

As indicated in FIG. 1, just below the rotary valve 41, a horizontal tube 52 communicates with the interior of the discharge tube from the rotary valve. The horizontal tube 52 communicates with the upwardly inclined portion of a conveying tube 53. The conveying tube 53 communicates with a horizontal portion 54 which enters a second cyclone-type centrifugal separator indicated generally at 56. The cyclone separator 56 is substantially identical to the cyclone 31 previously described in detail with reference to FIG. 3 and the tube 54 enters the cyclone at its periphery in the same fashion as the tube 21d enters the cyclone 31. The cyclone 56 includes a power driven fan (not shown) at its upper discharge 56a and this fan serves to lower the pressure within the tube 52, tube 53 and tube 54 so that material moving past the open end of the tube 52 is drawn into the collector tube 53. The cyclone 56 is characterized, as was the case with cyclone 31, by the formation in its interior of two concentric, helical flow paths of air, with entrained material moving out of the cyclone through its lower discharge passage 56b. The unloading of the cyclone 56 must, of course, be accomplished through an unloading valve which prevents entry of air back up into the cyclone through the passage 56b. The fiberized material moving downwardly through the passage 56b is directed into the throw-out cone 57 which communicates through the tube 58 with a conventional bagger apparatus 59.

In operation, molten slag is directed onto the rotating spinner 13 and is centrifuged tangentially outwardly from the periphery of the spinner. The steam blast from the jets 16 strips the attenuated slag from the spinner and fiberizes it, projecting the fibers into the open end 21c of the slightly conical horizontal tube 21b which is aligned concentrically with the rotational axis of the spinner. The heavier shot, or unfiberized slag, tends to fall outwardly of the perimeter of the tube end 21c and the fibers and only a minimum of shot enters the tube 21.

The sub-atmospheric pressure maintained in tube 21 by the fan 32 (FIG. 3) causes the fiber to travel up the inclined tube 21. This cools the fiberized material and prevents matting together of the fibers. In passing through the primary cyclone 31 the fiber is collected and concentrated. The material is dropped from the rotary valve 41 and across the mouth of the horizontal, air pick-up tube 52. This permits the tube 52 (the inte-

rior of which is under sub-atmospheric pressure because of the operation of the fan incorporated in the secondary cyclone 56) to draw in the lighter fibers while the heavy, unfiberized shot and slugs fall past the tube 52 and out of the system.

The method results in an unmatted, consistent, fiberized product characterized by minimum presence in it of shot or unfiberized slugs. No large collecting or settling chamber is necessary. Conveyor screens, rotary 10 screen cleaning apparatus and granulator apparatus, conventionally utilized, are unnecessary. Because a suction type conveying system is used, leaks are inward and little or no dust or fiber can migrate to the exterior surrounding area. The spacing of the open end of the 15 conical, horizontal tube 21b from the point of entry of the molten slag into the steam flow is such as to cause the heavier shot to move to the outside of tube 21b, without entering the tube, and these heavier particles, inherently formed in the fiberizing process, are thus excluded 20 from the system early in its process.

We claim:

1. A method of producing a homogeneous mineral fiber product from a stream of molten slag comprising:
25 rectilinearly projecting and fiberizing the slag by entraining it in an annularly arranged array of steam jets; providing a collecting tube concentric with the annular array of steam jets for receiving the fiberized material with the open receiving end of the tube spaced from the point of entry of the slag into the steam flow and having
30 a diameter somewhat less than the of the remainder of the tube to provide a conical entry section; connecting the end of said collecting tube remote from the entry section to an initial cyclone-type centrifugal separator; dropping the discharge from the lower end of the cyclone separator through an unloading valve; drawing off the fiberized material of lesser mass through a horizontal tube communicating with the discharge from the unloading valve; providing a conveying tube communicating with the horizontal tube and with the intake of
35 a second cyclone-type centrifugal separator; providing air moving fans for establishing suction in said collecting tube, horizontal tube, conveying tube and said centrifugal separators; and providing a means for accumulating the homogeneous product issuing from the lower
40 end of the second centrifugal separator.
45

2. A method as claimed in claim 1 in which the unloading valve utilized takes the form of a rotary valve.

3. A method as claimed in claim 1 in which both said collecting tube and conveying tube are inclined approximately 40° from the horizontal and connected to their respective separators at their high ends.

4. An apparatus for producing a homogeneous mineral fiber product from a stream of molten slag comprising: means for fiberizing the slag by entraining the slag stream in an annularly configured horizontal steam jet, a collecting tube having its open end spaced from the point of entry of the slag into the steam jet and concentrically aligned therewith for receiving the fiberized material, said receiving end of the collecting tube having a diameter somewhat less than that of the remainder thereof to provide a horizontal conical entry section, an initial cyclone-type centrifugal separator having its intake connected to the end of said collecting tube remote from said entry section, means for reducing the pressure in said collecting tube and separator to sub-atmospheric, an unloading valve receiving the discharge of the separator, a conveying tube having a hori-

zontal portion communicating with the vertically falling discharge from said unloading valve, a second cyclone-type centrifugal separator having its intake communicating with said conveying tube, means for reducing the pressure in said conveying tube and said second separator below atmospheric, and means for accumulating the material discharged from said second separator.

5. Apparatus as claimed in claim 4 in which both said collecting tube and conveying tube, beyond their entry section and horizontal portion respectively, are inclined approximately 40° from the horizontal and con-

nected to their respective separators at their high ends.

6. Apparatus as claimed in claim 1 in which the space between said open end of the collecting tube and said point of entry of the slag into the steam jet is in the 5 range of 100 to 120 percent of the diameter of said open end of the collecting tube.

7. Apparatus as claimed in claim 1 in which the space between said open end of the collecting tube and said point of entry of the slag into the steam jet is approximately 10 24 inches and the diameter of said open end of the collecting tube is approximately 22 inches.
